UNITED STATES PATENT OFFICE.

HORATIO S. EARLE, OF DETROIT, MICHIGAN.

DESIGN FOR A CORN-KNIFE.

SPECIFICATION forming part of Design No. 30,876, dated May 30, 1899.

Application filed May 3, 1899. Serial No. 715,483. Term of patent 14 years.

To all whom it may concern:

Be it known that I, HORATIO S. EARLE, a citizen of the United States, residing at Detroit, in the county of Wayne, State of Michigan, have invented and produced a new and original Design for a Corn-Knife; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to a new and original design for a corn-knife.

In the accompanying drawings, Figure 1 is an elevation of one side of my design. Fig. 2 is an elevation of the reverse side thereof. Fig. 3 is an enlarged transverse section on line 3 3 of Fig. 1.

The leading feature of my design consists in a backwardly-curved blade having formed in one face thereof, adjacent to and parallel with the line of the back, a depression or channel extending from the end of the blade to the handle, producing on the reverse face of said blade a raised bead, which also extends the entire length of said blade. The general shape of the blade is tapering from the back to the edge thereof, while the opposed faces of said blade are generally flat except for the raised bead thereon and the channel therein.

A designates the body of the blade; B, the curved back thereof; C, the curved edge of the blade; D, the depressed channel, and E the raised bead.

Having described my design, what I claim is—

The design for a corn-knife substantially as herein shown and described.

In testimony whereof I sign this specification in the presence of two witnesses.

HORATIO S. EARLE.
